UNITED STATES PATENT OFFICE.

JOSEPHINE ALTSHULER, OF NEW WHATCOM, WASHINGTON.

DESIGN FOR A GAME-BOARD.

SPECIFICATION forming part of Design No. 30,210, dated February 14, 1899.

Application filed January 21, 1899. Serial No. 702,990. Term of patent 3½ years.

To all whom it may concern:

Be it known that I, JOSEPHINE ALTSHULER, a citizen of the United States, residing at New Whatcom, in the county of Whatcom and State of Washington, have invented and produced a new and original Design for a Game-Board, of which the following is a specification.

This invention relates to a new and original design for a game-board; and it has for its object to provide a design of this character that shall be both useful and ornamental.

The leading feature of the design resides in a game-board provided on its playing-surface with a map-picture having within the plane of its field of water a plurality of ship-like figures and the bust-outline of a man arranged transversely of and directly across each of said ship-like figures.

While the essential feature of the design resides in the map-picture having thereon ship-like figures and the bust-outline of a man arranged across each of said figures, the invention involves certain minor features, which are the game-board provided on its playing-surface with separate map-pictures, one of which is inclosed within a rectangular space at one corner of the board. An additional minor feature is having separate groups of the ship-like figures and bust-outlines of men, respectively, within the water-space of the separate map-pictures.

In the drawings, Figure 1 is a plan view of a game-board embodying the design contemplated by the present invention. Fig. 2 is a sectional view of the game-board.

Referring to the accompanying drawings, the numeral 1 designates a rectangular game-

board provided with a flat playing-surface 2. The flat playing-surface 2 of the game-board 40 is provided thereon with separate map-pictures, one of which is inclosed within a rectangular space 3 at one corner of the game-board. The main map-picture represents the island of Cuba and a large field of water surrounding the same, while the smaller map-picture within the rectangular corner-space 3 preferably represents the bay of Manila in the Philippine islands, and within the water space or field of both map-pictures appear a 45 plurality of ship-like figures 4. The ship-like figures 4 are all arranged with their pointed ends disposed in the same direction and longitudinally of the game-board, and associated with each of the ship-like figures 4 is the bust-outline 5 of a man. The bust-outline 5 of a man is arranged transversely of and directly across each of said ship-like figures.

The entire map-picture is symbolical of the recent war between the United States and 60 Spain, and especially of the naval victories of Santiago de Cuba and of Manila bay, the ship-like figures being representative of the war-ships of the United States and the bust-outlines being representative of the commanding officers of the different ships.

What is claimed is—

The design for a game-board, herein shown and described.

In testimony that I claim the foregoing as 70 my own I have hereto affixed my signature in the presence of two witnesses.

JOSEPHINE ALTSHULER.
